Inventor,
H. Genembre Hubert, Esq.

United States Patent Office.

H. GENGEMBRE HUBERT, OF NEW YORK, N. Y.

Letters Patent No. 72,643, dated December 24, 1867.

IMPROVEMENT IN GAS-REGULATORS.

The Schedule referred to in these Letters Patent and making part of the same.

TO ALL WHOM IT MAY CONCERN:

Be it known that I, H. GENGEMBRE HUBERT, of the city of New York, county and State of New York, have invented certain Improvements in Gas-Regulators; and I do hereby declare that the following is a full and exact description thereof, which will enable others skilled in the art to make and use the same, reference being had to the annexed drawings, in which—

Figure 1 is a sectional elevation of my improved gas-regulator through the line $z z'$, and

Figure 2 is a horizontal section of the same through $x x'$.

This invention relates to an improved gas-regulator or pressure-governor, constructed as hereafter described, in which the regulating-valve is moved by a multiplying-lever, acted upon by the deflection of a metallic partition.

Description.

A is the body of the instrument, which may be made of any convenient size, and of proper shape for having a large surface. B is the valve-box, in which is fastened the valve-seat K. S is the inlet for the gas, and T is the outlet for the gas. G is a thin partition or false lid, made of metal, of papier mache, vulcanized rubber, or any material having enough rigidity to remain in position, and yet enough flexibility to yield a little under the pressure of the gas or the weight of the weights W. The metallic diaphragm G is soldered or otherwise fastened tight to the body A of the instrument. L is a lever, having its fulcrum on a spring-piece, P, which is riveted at one end to the body A of the instrument, and by means of the screw D and key F, the fulcrum of the lever L can be at any time adjusted nearer or further from the diaphragm G. E is a link connecting the centre of the diaphragm G to the lever L, at a point not very distant from the fulcrum thereof. At the other end of the lever L, at a greater distance from the link E than there is from E to the fulcrum, the conical valve V is suspended by a proper link, so that the least variation in the position of the lever, caused by the deflection of the diaphragm at the point E, will cause a great variation in the position of the valve V. H is the top, placed over the instrument to protect the diaphragm, and I is the lid, which can be removed to change the weights W.

Operation.

The pipe S being connected with the gas-supply pipe, and the pipe T with the gas-consuming pipe, the weights are regulated according to the pressure of gas in the supply-pipe, and by lighting the maximum and the minimum number of burners in the consumer's pipe, the proper position of the valve is regulated by altering the fulcrum of the lever L by means of the key F and screw D.

Claims.

I claim, in instruments for regulating the pressure of gas or vapors for illuminating purposes—

1. The use of a metallic diaphragm.
2. The combination of the diaphragm G, link E, lever L, and valve V, arranged substantially in the manner set forth.
3. Making the fulcrum of the lever L adjustable from outside the instrument by means of a screw, D, arranged as described, or any mode substantially the same.
4. The use of a lever for multiplying the sensitiveness of a gas-regulator, by increasing the throw of the valve thereof.

H. GENGEMBRE HUBERT. [L. S.]
